United States Patent

Des. 241,511
Patented Sept. 21, 1976

241,511

MODULAR HINGE

M. Vincent Sanderford, 130 Pearson Drive, and Philip J. Davis, Rte. 3, P.O. Box 279, both of Morganton, N.C. 26865

Original design application Sept. 14, 1974, Ser. No. 392,202, now Patent No. 236,797. Divided and this application Jan. 3, 1975, Ser. No. 538,312

Term of patent 14 years

Int. Cl. D8—09

U.S. Cl. D8—189

FIG. 1

FIG. 2

FIG. 3

FIG. 4

FIG 8

FIG. 1 is a front view of a double leaf hinge embodying the present invention,

FIG. 2 is a rear view of the double leaf hinge shown in FIG. 1,

FIG. 3 is a top view of the double leaf hinge shown in FIGS. 1 and 2,

FIG. 4 is a top and front perspective view of the double leaf hinge shown in FIGS. 1, 2 and 3,

FIG. 5 is a front view of a modified double leaf type hinge, similar to the hinge shown in FIG. 1,

FIG. 6 is a rear view of the hinge shown in FIG. 5,

FIG. 7 is a top view of the modified double leaf hinge shown in FIGS. 5 and 6, and, finally

FIG. 8 is a front and side perspective view of the modified double leaf type hinge disclosed in FIGS. 5, 6 and 7.

This is a division of application Ser. No. 392,202, filed Sept. 14, 1974, now Pat. D. 236,797, granted Sept. 16, 1975.

We claim:

The ornamental design for a modular hinge, as shown and described.
